UNITED STATES PATENT OFFICE

HERBERT F. OBERGFELL, OF RIVER FOREST, ILLINOIS, ASSIGNOR TO RESERVE HOLDING COMPANY, OF KANSAS CITY, MISSOURI, A CORPORATION OF DELAWARE

AUTOMATIC SWITCH

Application filed August 6, 1928. Serial No. 297,829.

The invention in this application relates in general to automatic telephone systems, but more particularly, it relates to the automatic switching devices employed in such a system for establishing talking connections between calling subscribers' lines and called subscribers' lines.

The particular switch concerned in this application is what is commonly known as a plunger type lineswitch, being a switch of the non-numerical type which is individual to a subscriber's line and operates to connect the calling subscriber's line to an idle one of a group of switches common to a number of subscribers' lines and comprising the first numerical switch of the switch train.

In the past it has been necessary in systems where plunger type line switches are used, to employ a master switch for controlling the movement of the plungers of the line-switches. Since the functions of the master switch are well known, they will not be described since the master switch itself, does not constitute a part of the present invention. In systems of only a few lines, the provision of a master switch entails considerable expense, so I have assumed as the principal object of this invention the provision of an individually driven plunger type lineswitch, thus eliminating the necessity of having a master switch.

One feature lies in the arrangement for controlling the movement of the plunger in seeking an idle trunk after the removal of the calling subscriber's receiver from the switch hook preparatory to the operation of the calling device, whereby the plunger hunts in both directions for an idle trunk, that is, from trunk 1 to 10 and then from trunk 10 to 1.

Other objects and features will be apparent from a perusal of the detailed description and claims which follow, when taken in conjunction with the drawings in which—

Fig. 1 is a top view of the switch assembly; Fig. 2 is a sectional view of the plunger and bank taken along the line 2—2 looking from the left;

Fig. 3 is a diagrammatic showing of the operating circuit of the lineswitch.

A detailed description of the construction of the switch will now be given, reference being had particularly to Fig. 1.

Similar numerals refer to similar parts throughout the several figures.

Reference numeral 4 indicates the mounting plate upon which all of the equipment of the switch is mounted. The switch bank 5 is similar in construction to that shown and described on page 38 of Vol. II of the bulletin entitled "Principles of Automatic Telephone" by Harry P. Mahoney, which bulletin is published by the Automatic Electric Inc., of Chicago, Illinois. This bank is mounted and held in position by the posts 6 and 7 which are rigidly screwed to the plate 4 from the back side. This bank is provided with an extra set of ten contacts 8 which protrude from the bank assembly on the side nearest the plate 4 and parallel thereto. The purpose of these contacts will be explained a little later.

Located in front of the contact bank is the disc 9 which is rotatably mounted on the plate 4, being separated therefrom by a thick washer which is not visible in the drawings. The disc 9 is held on the pivot shaft by nut 10.

Rigidly fastened to the underside of the disc 9 is a ratchet wheel 11 (shown dotted) which has for its purpose the rotating of disc 9.

Cut to a depth of approximately one-eighth of an inch in the upper surface of the disc 9 is the heart-shaped channel 12. The purpose of that channel will be explained later.

The plunger 13 is mounted on the plate 4 by means of a standard (not visible) which is of such a size as to hold the plunger above the disc, the plunger being pivotally mounted on the standard at 14. The plunger 13 is made up of two flat pieces 15 and 16, with 16 lying on top of 15. The end of parts 15 and 16 are shown in Fig. 2. Piece 15 carries the pivot 14 and its only motion is a rotary motion about the pivot 14. To the underside of the piece 15 is fastened the roller 17 which rides in the channel 12 of disc 9. On the upper side of 15 are the two small posts 18 and 19. Member 16 has two long slots in

55

60

65

70

75

95

100

which those two posts fit. The tops of the posts are wider than the slots to prevent 16 from separating from 15. With this arrangement 16 is slideable along 15. The end of 16 which is adapted to operate the springs of the contact bank is arrow shaped and carries the roller bushings 20, best seen in Fig. 2.

On the underside of 15 is rigidly fastened the wiper 21 which is so placed as to rub 10 the contacts 8 of the bank as plunger 13 is rotated.

To the left of the disc is located one of the operating magnets 22 of the switch. The heel piece of this magnet is fastened directly 15 to plate 4 by means of screws. This magnet has an armature 23 which carries a pawl 24 near one of its extremities. The pawl 24 is adapted to engage the teeth of ratchet. Armature 23 is pivotally mounted on the heel piece at 25. Upon each attraction of the 20 armature, the pawl 24 is advanced one tooth and when the magnet deenergizes the pawl and ratchet causes the disc 9 to be rotated a given amount, the motive power being provided by spring 26 fastened to the 25 plate 4 and to the end of armature 23. The stop 27 is engaged by pawl 24 limiting the movement of the pawl and locking it in the teeth of the ratchet. Spring 28 holds pawl 30 24 against the teeth during its movement.

The opposite end of the armature 23 is provided with a bushing to insulate it from the spring 29 which it operates upon each energization of magnet 22.

35 Resilient member 36 is employed to prevent reverse, or clockwise, movement of the disc 9. It is fastened to the right angle bracket 37 which in turn is fastened to the plate 4.

40 To the right of the disc 9 is another operating relay 30. The heel piece of this relay is rigidly secured to the plate 4. Relay 30 is provided with two armatures, pull-down armature 31 and bridge-cut-off armature 32. 45 Both of these armatures are pivoted in the usual manner to the heel piece at 33. An aperture in the armature 31 allows the bent over position of the armature 32 to pass through it to complete a closed magnetic circuit with the core of the relay.

50 One end of the armature 31 is made fork shaped as shown in the drawings. The prongs of this fork fit one on either side of the pin 34 which is secured to the member 16 of plunger 13. Resilient member 35 cooperates with the other end of armature 31 to hold the armature away from the end of the core when the relay is not energized.

60 The end of the BCO armature not in the magnetic circuit is used in the usual manner to operate springs.

65 When the pull-down armature is attracted to the core of the relay, the member 16 is moved on the member 15 and plunged into the bank to operate the contacts in the well

known manner. The normal position of armature 31 holds the plunger out of the bank.

Screw 38 is used as a backstop for armature 31 and it is threaded into a portion of the heel piece which is bent upwards from 70 the plate 4.

If it is desired to rotate the plunger 13 to seek an idle trunk, circuit connections will energize magnet 22. This magnet then attracts its armature 23 thereby moving the pawl 24 into engagement with the tooth next to that with which it was at that time engaged. When the magnet 22 is deenergized, armature 23 retracts, and under the influence of spring 26, pawl 24 rotates the disc 9 one step in a counter clockwise direction. The rotation of disc 9 through the action of roller 17 rolling in channel 12, the sides of which act as a cam, rotates the plunger 13 one step about pivot 14. In the position in which the disc 9 is shown in the drawing, that rotation is in a counter clockwise direction. When the roller 17 passes the end of the heart-shaped channel, the direction of rotation of plunger 13 is reversed. At this point, the plunger is standing opposite the left hand set of contacts of bank 5. Thus it can be seen that the rotation of disc 9 in one direction will cause the rotation of plunger 13 in both directions, thus moving from trunk 1 to trunk 10 and then from trunk 95 10 to trunk 1 stopping at idle trunks between.

The bank and wiper arrangement shown in Fig. 2 will now be explained. The upper of the pair of contacts 8 in each set, the right-hand one in Fig. 2, take the place of a contact similar to the contact 39, being made longer so as to protrude farther from the bank so that wiper 21 can make a wiping contact with it and with its associate contact. A pair of 100 these contacts 8 are provided for each trunk and are the test contacts of the trunks accessible to this switch, ground being connected to this contact when the associated trunk is in use to prevent seizure of the trunk by any line switch.

It will be noted that the spring 40 when operated by the plunger makes contact with one of the set of contacts 8.

A description of the construction of the 115 switch having been given, a detailed description of the operation will now be related, reference being had particularly to Fig. 3. In that figure, LS designates the individually driven lineswitch of this application; conductors 42 and 44 are the line conductors connecting the line switch to the subscriber's station to which it is individual and which has the usual talking, receiving and signaling instrumentalities and which is also 120 equipped with a well known impulse sender or calling device, the substation equipment not being shown on the drawing for sake of simplicity; the private conductor 43 which is multiplied to the banks of all of the final 125 130

connector switches having access to that substation; and the selector E which is of the well known type of Strowger selector having wipers adapted to be moved in a vertical direction and thence a rotary direction under control of the calling device at the substation, only enough of the selector being shown which is necessary for an understanding of this invention.

10 When the subscriber desires to initiate a call, he removes his receiver from the hook and in so doing he completes a loop circuit including the receiver and transmitter in series with the line conductors 42 and 44. The closure of the loop circuit completes a circuit for line relay 45 of lineswitch LS. This circuit is traceable from ground through the left hand set of contacts of the off-normal springs, conductor 47, conductor 44, over the subscriber's 15 loop circuit, conductor 42, conductor 46, right hand contact set of off-normal springs, winding of line relay 45 to grounded battery. Relay 45 energizes in that circuit and operates its armature to move the associated springs 20 into engagement with their make contacts. The engagement of spring 48 with its grounded make contact places ground on the test contacts associated with that line in the banks 25 of the connector switches having access thereto, by placing ground on conductor 43. The engagement of spring 49 with its make contact completes a circuit for relay 51 and magnet 22 in series. The engagement of spring 50 prepares a circuit joined between the relay 30 51 and magnet 22.

The operation of this switch from this point on depends upon the trunk condition, that is, whether or not the trunk opposite which the plunger of the lineswitch is standing is idle. It will first be assumed that it is 40 idle, in which case the relay 51 will operate when its circuit is completed. Relay 51 is of a high enough resistance as to prevent magnet 22 energizing in series with it.

45 The operation of relay 51 moves its spring 52 into engagement with its grounded make contact thereby completing the obvious circuit for the pull-down winding of operating relay 30, which winding energizes and attracts its two armatures 31 and 32. The operation of pull-down armature 31 plunges the plunger into the bank thereby causing springs 53 and 54 to engage springs 55 and 56 and spring 40 to engage spring 8. 50 The operation of bridge cut-off armature 32 moves the off-normal springs out of engagement with their back contacts thereby opening the circuit of line relay 45 which deenergizes and opens the circuit of relay 51. 55 Relay 51, because of the copper slug on the heel end of its core, is slow to release and remains energized an interval after its circuit is opened.

The engagement of springs 53 and 54 with 60 springs 55 and 56, respectively completes the

following circuit for line relay 64 of selector E:

From ground, through the lower winding of relay 64, conductor 63, back contact and spring 61 of switching relay 69, conductor 70 59, spring 56, spring 54, conductor 44, substation loop circuit, conductor 42, spring 53, spring 55, conductor 58, spring 60 and its back contact, conductor 62, and upper winding of relay 64 to grounded battery. 75

Relay 64 operates in that circuit and moves its spring 65 into engagement with its front contact, completing the circuit of release relay 66 which energizes and at its spring 67 places ground on release trunk conductor 68. 80 That ground is extended to the BCO winding of relay 30 via contact 8 and spring 40 before relay 51 deenergizes.

When relay 51 deenergizes it opens the circuit of the pull-down winding of relay 30 at 85 52. However, armatures 31 and 32 will be held attracted by the BCO winding of relay 23.

The ground on conductor 68 will also be extended to conductor 43 to substitute for the 90 ground removed therefrom when relay 45 deenergized.

The selector E may now be controlled by the calling device for extending the connection to the next switch in the switch train in 95 the well known manner.

It will be assumed now that when the line switch LS was seized, its plunger was standing opposite a busy trunk, in which case a ground potential would be present upon the set of contacts 8 associated with that trunk. That presence of ground will be conducted to magnet 22 via wiper 21, conductor 57, and spring 50 and its make contact. Thus magnet 22 will energize and interrupt its energizing circuit by moving spring 29 out of engagement with its make contact. Magnet 22 deenergizes and rotates the plunger 13 (Fig. 1) and wiper 21 to the next set of contacts as has previously been explained. 100 Ground on conductor 57 will short circuit relay 51 before it has had a chance to operate, thus preventing relay 51 from operating and plunging the plunger in the bank to connect the calling subscriber to a busy trunk. 110

If the next trunk should be busy, wiper 21 will encounter ground again and magnet 22 will energize and deenergize to again advance the plunger. When an idle trunk is encountered, noted by the absence of ground on the associated set of contacts 8, relay 51 will not be short circuited and it will operate as previously described. 115

At the termination of the call, the replacement of the receivers opens the substation loop circuit and the switches release, removing ground from conductor 68, thus opening the circuit of the BCO winding of relay 30 to release the armatures 31 and 32 to remove 120 125 130

the plunger from the bank and prepare the switch for another call.

When the line switch LS is seized by a connector switch on calls incoming to the substation associated with LS, the connector will connect ground to conductor 43 to energize the BCO winding of relay 30 to operate only the armature 32, thereby opening the off-normal springs to prevent the removal of the receiver from the switch-hook completing the circuit of the line relay 45.

Having thus described my invention, what I consider new and desire to have protected by Letters Patent is pointed out in the appended claims.

What is claimed is:

1. The combination, within a plunger type lineswitch, of a plurality of sets of bank contacts, means for rotating the plunger to position it opposite the bank contacts of an idle trunk after the seizure of the switch by a calling line, with means for plunging the plunger into the bank to operate said contacts.
2. In an automatic switch, a normally stationary plunger, a bank comprising sets of contacts adapted to be operated by the plunger, each contact set being the terminus of a trunk, means for rotating said plunger step-by-step to position it opposite the contact set of an idle trunk, and means responsive to said positioning for plunging the plunger into said bank to operate said contacts.
3. In an automatic switch, a plunger, a bank comprising sets of contacts adapted to be operated by said plunger, each contact set being the terminus of a trunk, a test contact associated with each contact set, a wiper carried by said plunger and adapted to wipe said test contacts, each test contact having ground potential thereon when the associated trunk is busy, means responsive to the encountering of ground potential by said wiper when the switch is seized by a calling line for positioning said plunger opposite a contact set whose associated test contact has not ground potential thereon, and means responsive to said positioning for plunging said plunger into the bank to operate said contacts.
4. In an automatic switch, a pivoted plunger, a bank comprising sets of contacts, each set being the terminus of a trunk, a rotatable eccentric, means for rotating said eccentric to rotate said plunger about its pivot, to position it opposite the contact set of an idle trunk, said eccentric being of such shape as to rotate said plunger first in one direction then in another, and means responsive to said positioning to plunge said plunger into said bank to operate said contacts.
5. In an automatic switch, a pivoted plunger, a bank comprising sets of contacts, each set being the terminus of a trunk, a rotatable disc pivoted at its center, a channel eccentrically placed in said disc, means for rotating said disc, a roller on said plunger cooperating with said channel to rotate said plunger about its pivot to position it opposite the contact set of an idle trunk, said channel of such a shape as to cause the plunger to be rotated back and forth before the same group of trunks, and means responsive to said positioning for plunging said plunger into the bank to operate said contacts.

6. In a telephone system, a subscriber's line, an automatic switch having a plunger and associated with said line, trunk lines terminating in the bank of said switch, each trunk terminating in a set of contacts individual thereto and adapted to be operated by said plunger, means in said switch and operated responsive to the initiation of a call on said line for positioning the plunger opposite the contact set of an idle trunk, and means in said switch for plunging said plunger into the bank to operate said springs to connect said line to the idle trunk.

7. In an automatic switch, a pivoted plunger, a bank comprising sets of contacts, each set being the terminus of a trunk, a rotatable cam, means for driving said cam continuously in one direction to rotate said plunger in both directions of rotation to position it opposite the contact set of an idle trunk, and means responsive to said positioning to plunge said plunger into said bank to operate said contacts.

8. In an automatic switch, a plunger, a bank comprising sets of contacts adapted to be operated by said plunger, each contact set being the terminus of an outgoing trunk, said plunger standing opposite the trunk last used when the switch is idle, means within said switch and responsive to the seizure of the switch by a calling line for plunging said plunger to operate the contacts of the trunk opposite which it is standing if that trunk is idle, and means within said switch for rotating said plunger to position it opposite the contact set of an idle trunk if the trunk opposite which it is standing is busy, said last means preventing the operation of said first means until said positioning takes place.

9. In combination, within an individual line switch, a plunger for operating bank contacts, electromagnetically controlled means for rotating the plunger to position it opposite the bank contacts of an idle trunk after the seizure of the switch by the associated calling line, and electromagnetic means for plunging said plunger into the bank to operate said contacts.

10. In an automatic switch, a pivoted plunger, a bank comprising sets of contacts, each set being the terminus of a trunk and adapted to be operated by said plunger, means within said switch for rotating said plunger step-by-step in both directions of rotation to position it opposite the contact

set of an idle trunk, and means responsive to said positioning for plunging said plunger into the bank to operate said contacts.

11. In a telephone system, a subscriber's line, an automatic switch individual to said line, said switch having a plunger and a test wiper comprising a unitary structure, a bank comprising sets of contacts, each set being the terminus of a trunk and comprising contacts adapted to be operated by said plunger and an auxiliary contact to be wiped by said wiper, said auxiliary contact having ground potential thereon when the associated trunk is busy, means for rotating said unitary structure step-by-step when said subscriber's line initiates a call and as long as said wiper encounters ground potential on said auxiliary contacts, to position the plunger opposite the contact set of an idle trunk, and means responsive to the failure of said wiper to encounter ground on an auxiliary contact for plunging said plunger to operate the other contacts of the set to connect said subscriber's line to the idle trunk.

25 12. In an automatic switch, a set of contacts including line contacts and a test contact, a carriage provided with a wiper and a plunger, means for rotating said carriage to place said wiper in contact with said test contact, and separate means for plunging said plunger into said contact set to operate said line contacts into engagement with each other.

35 13. In an automatic switch, a set of contacts including pairs of line contacts and a test contact, a carriage provided with a plunger and a wiper, means for rotating said carriage to position said wiper in contact with said test contact, and means responsive to said positioning for operating said plunger to operate the line contacts of each pair into engagement with each other, said last means preventing the further operation of the first means to hold said wiper in contact with said

40 45 test contact.

14. In an automatic switch, a bank comprising sets of contacts, each set including line contacts and a test contact, a carriage provided with a wiper and a plunger, means for rotating said carriage to wipe said wiper over said test contacts to find an idle contact set, and separate means responsive to the finding of an idle contact set to plunge said plunger into said bank to operate the line contacts of the idle set into engagement with each other.

50 55 In witness whereof, I hereunto subscribe my name this second day of August, A. D. 1928.

HERBERT F. OBERGFELL.
